UNITED STATES PATENT OFFICE.

CHAUNCEY COUTANT, OF CRAWFORDSVILLE, INDIANA.

DESIGN FOR A CORNER-POST FOR WAGON-BODIES.

SPECIFICATION forming part of Design No. 17,697, dated September 6, 1887.

Application filed March 23, 1887. Serial No. 232,177. Term of patent 7 years.

To all whom it may concern:

Be it known that I, CHAUNCEY COUTANT, a citizen of the United States, residing at Crawfordsville, in the county of Montgomery and 5 State of Indiana, have invented and produced a new and original Design in Corner-Posts of Buggy-Bodies, of which the following is a specification, reference being had to the accompanying drawing, forming part thereof.

10 The figure shows a sectional view of the corner of a buggy-body representing my design of a corner-post.

A is the corner-post of the buggy-body, and B B indicate the panels adjacent thereto.

15 My design consists in the corner-post A, whose shape and configuration is as follows: The two faces d f and d' f are at right angles to each other and are plane surfaces.

20 d b a and d' b' a' are acute-angled grooves cut into the post. The faces a b and a' b' of the two grooves are parallel, respectively, to the faces d f and d' f' of the corner-post.

25 The outline from a to a' is as follows, to wit: from a to c a curved surface concave toward b. From c toward the face d' f the surface is

plane and perpendicular to the face d' f. From a' to c' the surface is curved and is concave toward b'. From c' toward the face d f the surface is plane and perpendicular to the face d' f. The two surfaces which have been specified as extending, respectively, from c and c' perpendicular, respectively, to the faces d' f and d f are united by a curved surface convex toward f. 30

I claim—

35 In a design for a wagon-body, the corner-post thereof, consisting of two plane surfaces, d f and d' f, perpendicular to each other, and of the two acute-angled grooves d b a and d' b' a', having the faces a b and a' b' of the grooves 40 parallel, respectively, to the two plane surfaces d f and d' f, and consisting, further, of the curved surfaces a c and a' c', and also of the two plane surfaces extending from c and c', united by a curved surface, as herein described and shown.

CHAUNCEY COUTANT.
